United States Patent Office

Des. 190,400
Patented May 23, 1961

190,400

BOAT

William R. Tritt, Newport Beach, Calif., assignor to
Glasspar Company, Santa Ana, Calif., a corporation
of California

Filed Oct. 27, 1959, Ser. No. 58,080

Term of patent 14 years

(Cl. D71—1)

FIG. 1.

FIG. 2.

FIG. 3.

FIG. 4.

FIG. 5.

Fig. 1 is a perspective view of a boat, showing my new design;

Fig. 2 is a top plan view thereof;

Fig. 3 is a side elevation thereof;

Fig. 4 is a front elevation thereof; and

Fig. 5 is a rear elevation thereof.

The dominant features of my design reside in the portions shown in full lines.

I claim:

The ornamental design for a boat, as shown and described.
